UNITED STATES PATENT OFFICE.

FREDERICK A. BALLOU, JR., OF PROVIDENCE, RHODE ISLAND, ASSIGNOR TO B. A. BALLOU & COMPANY INC., OF PROVIDENCE, RHODE ISLAND, A CORPORATION OF RHODE ISLAND.

NECK CHAIN.

Application filed July 20, 1921. Serial No. 486,067.

To all whom it may concern:

Be it known that I, FREDERICK A. BALLOU, Jr., a citizen of the United States, residing at Providence, in the county of Providence and State of Rhode Island, have invented certain new and useful Improvements in Neck Chains, of which the following is a specification.

This invention relates to an improved adjustable neck chain or the like, and has for its object to provide a simple and practical adjustment for an ornamental chain of this character from which a pencil, eyeglass, locket or other pendant may be suspended whereby the operating length of the chain may be readily adjusted to suit the convenience of the user and automatically locked in adjusted position against strain which may be brought upon the supporting end of the chain, which adjustment is frequently desired where an article of use such as a pencil or eyeglass is suspended on such a chain or cord about the neck of the wearer.

With these and other objects in view the invention consists of certain novel features of construction, as will be more fully described, and particularly pointed out in the appended claims.

In the accompanying drawings:—

Figure 1 is a view illustrating in outline the general arrangement of my improved adjustable neck chain.

Figure 2 is an enlarged view illustrating the clutch member as disengaged to permit a free movement of the suspending part of the chain through the clutch casing.

Figure 3 is a view illustrating the locking action of the clutch when a strain is brought upon the suspending part of the chain below the clutch casing, showing that member of the chain as locked in its casing.

Figure 4 is a top view of the clutch casing showing the two opposite holes therein.

Figure 5 is a detail of the locking member of the clutch casing, showing the binding enlargement member with a rigid stem therein to which one part of the chain is connected.

It is found in practice desirable to provide a simple and effective clutching mechanism which is neat in appearance, to be applied to a neck chain or the like for locking the same in adjusted position and at the same time neatly securing one end of the chain to the adjustable portion of the clutch,

and the following is a detailed description of one means by which this result may be accomplished:—

With reference to the drawings, 10 designates the casing member of the clutch which is preferably formed in the shape of a hollow ball, but which may be made in any desired shape. In this ball I form upper and lower openings 11 and 12 through both of which one part 13 of the chain extends, 60 one portion 18 of this part below the clutch being connected to a pendant 19.

This chain is preferably shaped in loop form, as illustrated in Figure 1, to be extended to a size to be readily passed over the head, to engage the neck of the wearer, and to the end 15 of the opposite portion 14 of this chain is secured a rigid stem 16 which projects through the opening 11 and to its inner end is secured an enlargement 17 70 within the casing, to serve as a binding member for locking the opposite part 13 therein.

In assembling the parts I preferably form the opening 11 of a size to just receive the 80 enlargement 17 before the part 13 of the chain is passed therethrough. When this chain is subsequently passed through both the upper and lower openings 11 and 12 this enlargement cannot, of course, be withdrawn through this opening and, therefore, 85 when a tension is applied to that part of the chain below the casing the enlargement 17 is naturally drawn up into the position illustrated in Figure 3, thereby binding the 90 part 13 against the edge of the opening 11 securely locking the chain in adjusted position.

By mounting the binding enlargement 17 upon the lower end of the rigid stem 16, 95 when strain is applied to the chain below the casing this stem is caused to fulcrum upon the edge 20 of the opening 11 and so swing on this fulcrum over against the opposite edge 21 of this opening.

When it is desired to adjust the size of the looped portion of the chain it is only necessary to engage the lower portion 18 of the chain with one hand and the casing member 10 with the other hand, which latter member by moving either up or down to the desired position, regulates the operating length of the chain, but as soon as the casing is released and a strain applied to the part 18 alone, then the locking member 17 110

is drawn up to securely bind the part 13 in the casing to prevent further extension to the operating length of the chain.

I do not wish to be restricted to the use 5 of a neck chain having links, as a cord or other suitable flexible element may be employed for this purpose.

I have shown the casing as made in the 10 form of a hollow ball but I do not wish to be restricted to this particular shape of co-operating locking device as any suitable member for receiving both the chain and the enlargement for producing a binding 15 effect upon the chain, will fall within the spirit of this invention, its scope being limited only by the terms of the appended claims.

I claim:

1. The combination with a neck chain, of 20 a clutch casing slidably mounted thereon, the said casing being provided with openings through it through both of which one part of the chain loosely extends and a member of a size equal to the upper of said openings loosely suspended in said casing by an 25 end of the chain connected to the member through said opening whereby a pull upon the said part of the chain above said casing causes said member to lift and automatically 30 grip and lock the first said part of the chain against the wall of said casing.

2. The combination with a neck chain, of 35 a clutch member thereon comprising a hollow casing provided with upper and lower openings through both of which one part of

the chain loosely extends, and a member in said casing comprising a body of a size greater than that of the space left in the upper opening when the chain is extending therethrough and having a relatively rigid 40 stem extending out through said upper opening and connected at its outer end to an end of the chain, whereby a pull upon the second part above said casing causes said member to lift and automatically grip and 45 bind said first part of the chain against the edge of the upper opening.

3. The combination with an adjustable neck chain, of a clutch thereon formed of a hollow member having upper and lower 50 openings through both of which one part of the chain loosely extends, a binding member loosely mounted in said hollow member and having an enlargement of a size greater 55 than that of the space left in the upper opening when the chain is extending therethrough and having a relatively rigid stem extending out through the upper opening and connected at its outer end to an end of said chain whereby a tension applied to the 60 second part of said chain above said hollow member causes said binding member to lift to close the upper opening and fulcrum upon the edge of the upper opening when the said 65 part and end portion of the chain are non-parallel thereby gripping the said part of the chain against the wall and edge of the upper opening of the hollow member.

In testimony whereof I affix my signature.
FREDERICK A. BALLOU, Jr.
